THAWING AND STEAMING APPARATUS

Walter C. Elze, Forest Hills, N. Y., assignor to
Hauck Manufacturing Company, Brooklyn,
N. Y., a corporation of New York

Application January 19, 1932. Serial No. 587,510

4 Claims. (Cl. 122—23)

The invention relates to apparatus for developing water vapor under a high degree of superheat and suitable for thawing and steaming operations, for example, in the thawing of fire hydrants, frozen pipes, radiators, engines and the like, as well as the steaming of feathers and wearing apparel.

It has for a general object to afford apparatus of this character which shall be readily transportable, as on motorized fire apparatus in which no provision is made for the development of steam, and which heating apparatus also shall be of such a nature that it will not be too heavy or unwieldy, whereby it may be readily conveyed as a whole manually to the particular position for use, for example, in the thawing of fire hydrants.

A further object of the invention resides in the provision of a vapor-producing apparatus where-in vapor at an extremely high degree of superheat may rapidly and expeditiously be developed, for example, in the course of a quarter of a minute or less from the time of igniting burner apparatus associated therewith.

Another object of the invention resides in the provision of apparatus of this nature which shall be particularly safe in operation, the vapor being developed under relatively low pressures but with a high degree of superheat.

In carrying out the invention, a suitable supporting base is provided for mounting a container or the like which supplies fluid fuel under the required pressure to suitable burner apparatus associated with a vapor-generating device, the burner apparatus and vapor-generating device also being carried by said base. Where a gas main is available, of course, the fuel tank may be dispensed with; or, the tank may be provided as an entirely independent unit.

If desired, the base may be provided with up-standing handle members or the like for manually conveying the apparatus to the point of use.

The vapor generator is so designed that not only will vapor be rapidly developed therein but the same will be heated to a particularly high degree of superheat. This is accomplished by mounting the burner apparatus within the lower portion of a shell, provided with air openings at its lower part and open also at the top, this shell having secured thereto an annular water reservoir within which is co-axially located a helix of pipe. The latter communicates with the bottom of the water reservoir and at its upper end discharges into a vapor chamber or drum mounted above the shell and water reservoir and also in free communication with the latter.

To remove the vapor from this vapor chamber and at the same time provide the vapor with a high degree of superheat, a U-tube element is located, for example, substantially axially of the helix, one leg of said element terminating in the vapor chamber while the other may extend therethrough, as well as through a cover member for the shell and vapor chamber. The latter is also provided with discharge outlets for the products of combustion.

The last-named leg of the said superheater element is connected in suitable manner with a delivery hose or the like through which the highly heated water vapor is discharged for use.

The nature of the invention, however, will best be understood when described in connection with the accompanying drawing, in which:

Fig. 1 is a part front elevation and part vertical section of the novel apparatus.

Fig. 2 is a part plan and a horizontal section thereof, the latter being taken on the line 2—2, Fig. 1 of the drawing, and looking in the direction of the arrows, with cover member removed.

Referring to the drawing, 10 designates a suitable base or other means of support for the different parts constituting the novel thawing or steaming apparatus, the base being preferably provided with feet 11 to displace it vertically. This base is provided also with a socket or like locating member 12 for receiving and positioning 85 the fuel tank 13 adapted to contain a fluid fuel, such as acetylene or other hydrocarbon gas, etc., providing an intense heat for development of the water vapor. The said tank, furthermore, may be provided with suitable carrying straps 14 in replenishing the fuel supply by substitution of a filled tank for an exhausted one.

A pipe 16 connects the outlet 17 of the tank to suitable burner apparatus embodying, for example, the multiple burner elements 18. These 95 are located at the lower portion of an open-ended shell member 20 attached at the bottom to the base 10 and provided with the openings 21 to the atmosphere for furnishing oxygen for the combustion of the fuel in the burner apparatus.

Above this burner apparatus and secured in any suitable manner to the shell 20 and extending substantially to the upper end of the same is an annular cylindrical water reservoir 22, it being preferred to include an intermediate wall 23 of 105 refractory and thermally insulating material. Water is supplied to this reservoir through a combination valve and filler 24, and taps 25 are provided at various portions longitudinally of the reservoir to assure the proper level of the water 110

therein. At its top, the reservoir is in free communication, as through the pipe connections or tubular drains 26, with a sealed vapor chamber or drum 27. The bottom of the chamber is preferably more or less concavo-convex with convex portion at the center and the pipe connections at the lowest portion so that any condensation or water carried over from the reservoir will be immediately returned thereto and thus effecting 10 a complete separation of water and vapor.

Mounted co-axially within the shell and in the combustion space above the burner device, and thus surrounded by the water reservoir, is a helix or pipe coil 30 which connects at its lower 15 end 31 with the bottom of the reservoir and at its upper end 32 discharges the steam generated therein into the vapor chamber 27. The vapor is removed from the chamber 27 through a superheater element constituted by a U-tube located 20 substantially axially of the helix 30 and whose one leg 33 terminates in the chamber 27, the open end thereof being located at the uppermost portion of said chamber to insure against moisture passing into the same with the outgoing vapor. 25 and thus securing removal of the hottest vapor. The other leg 34 of this U-tube extends through the chamber and also through a top or cover member 35 mounted over the top of the shell and the chamber 27, said cover member being provided 30 with discharge openings 36 for the products of combustion, which then more or less envelope the outer portion of the leg 34 serving to maintain the superheat of the vapor thereby.

By means of a pipe 37, leg 34 is connected to 35 a flexible hose member or the like 38 having the nozzle 39 for discharging the highly superheated vapor for use. A safety valve 40 may be inserted in the pipe 37, if desired, to provide against any undue pressures which might develop through 40 clogging or other sealing of the nozzle.

In apparatus of the hereinbefore described character, speed of operation is an essential element, as well as the production of a high temperature, particularly in the provision of a dry 45 superheated vapor. This is attained by the novel apparatus, it having been found possible to develop a highly superheated vapor in less than one-quarter minute's time from the ignition of the burner device.

50 The proportions of the apparatus are such that an adequate supply of dry highly-heated steam or water vapor is furnished for a sufficient length of time; and when the supply of fuel is exhausted, a different filled container for the same may 55 readily be substituted for the exhausted one.

The apparatus as a whole, furthermore, is not unduly heavy or unwieldy and may conveniently be conveyed from place to place by two persons, upstanding handle members 41 for this purpose 60 being attached to the base 10, if desired. The burner-boiler element may, of course, be mounted independently of the fuel supply, but it is preferred, generally, to combine the same upon a single support, as the base 10 and as indicated.

65 The arrangement of the water reservoir as an annular member not only expedites the development of the vapor, but this layer of water serves as a thermally insulating element with respect to the outer shell portion over that part of the apparatus which is immediately above the burners and wherein the highest temperatures prevail.

I claim:

1. An apparatus of the character set forth, comprising means to supply fluid fuel under pressure, a steam generator including a metallic

shell, an annular water reservoir secured to the shell, a burner positioned beneath the water reservoir and connected with the fuel supply, a helix of pipe coaxially disposed within the annular reservoir and communicating with the bottom thereof, a vapor chamber above the shell and water reservoir and in free communication at its lowermost portion with the water reservoir and with the upper end of the helix above the said lowermost portion, superheater means mounted within the helix having one end in communication with the vapor chamber above the said lowermost portion thereof, and vapor delivery means attached to the other end of said superheater means. 80 85 90

2. An apparatus of the character set forth, comprising means to supply fluid fuel under pressure, a steam generator including a metallic shell, an annular water reservoir secured to the shell, a burner positioned beneath the water reservoir and connected with the fuel supply, a helix of pipe coaxially disposed within the annular reservoir and communicating with the bottom thereof, a vapor chamber above the shell and water reservoir, said chamber having a concavo-convex bottom, drains from the concavo portion thereof to the water reservoir and the upper end of the helix extending into said chamber above said concave portion, superheater means mounted within the helix having one end in communication with the vapor chamber above the concave portion thereof, and vapor delivery means attached to the other end of said superheater means. 95 100 105

3. An apparatus of the character set forth, comprising means to supply fluid fuel under pressure, a steam generator including a metallic shell, an annular water reservoir secured to the shell, a burner positioned beneath the water reservoir and connected with the fuel supply, a helix of pipe coaxially disposed within the annular reservoir and communicating with the bottom thereof, a vapor chamber above the shell and water reservoir and in free communication at its lowermost portion with the water reservoir and with the upper end of the helix above the said lowermost portion, a U-tube superheater element extending substantially axially through the helix having one leg terminating in the vapor chamber at its uppermost portion and the other 110 115 120 125 130 135 140 145 150 passing therethrough, and vapor delivery means attached to the outer end of said last-named leg of the U-tube.

4. An apparatus of the character set forth, comprising means to supply fluid fuel under pressure, a steam generator including a metallic shell, an annular water reservoir secured to and within the shell, a burner positioned beneath the water reservoir and connected with the fuel supply, a helix of pipe coaxially disposed within the annular reservoir and communicating with the bottom thereof, a vapor chamber above the shell and water reservoir and in free communication with the latter and with the upper end of the helix, a U-tube superheater element extending substantially axially through the helix having one leg terminating in the vapor chamber and the other passing therethrough, a cover over said shell and vapor chamber and having discharge openings to the atmosphere, the last-named leg of the U-tube passing also through said cover member, and vapor delivery means attached to the outer end of said last-named leg of the U-tube. 150
